UNITED STATES PATENT OFFICE.

WILLIAM F. DREW, OF OAKLAND, CALIFORNIA, ASSIGNOR TO GEORGE C. JENSEN, OF OAKLAND, CALIFORNIA.

LOCKING APPARATUS.

1,262,185.

Specification of Letters Patent. Patented Apr. 9, 1918.

Application filed November 27, 1917. Serial No. 204,271.

To all whom it may concern:

Be it known that I, WILLIAM F. DREW, a citizen of the United States, residing at Oakland, in the county of Alameda and 5 State of California, have invented certain new and useful Improvements in Locking Apparatus, of which the following is a specification.

The present invention relates to an improved locking apparatus designed for the interlocking of two intersecting, rotatably mounted, bodies together, whereby, when in interlocked engagement, said bodies are prevented from longitudinal movement relative to each other and one of said bodies is locked from rotation by the other.

To more fully comprehend the invention, reference is directed to the accompanying drawings, wherein—

20 Figure 1 is a sectional view taken on line 1—1 of Fig. 2, of the preferred embodiment of my invention.

Fig. 2 is a sectional view taken on line 2—2 of Fig. 1, viewed in the direction of 25 the arrows.

Fig. 3 is a view similar to Fig. 1, with one of the members rotated to permit rotative movement of the other, and taken on line 3—3 of Fig. 4.

30 Fig. 4 is a view similar to Fig. 2 taken on line 4—4 of Fig. 3.

Referring more particularly to the several views of the drawings, wherein like characters of reference designate corresponding parts, 1 indicates a suitable member provided with cylindrical bores 2 and 3 passing therethrough, said bores intersecting each other, as in the drawings. Rotatably mounted within the respective bores

40 are the cylindrical bodies 4 and 5, which also intersect, as in the drawing. The body 4 is provided at the point of intersection by the body 5 with a semi-circular recess 6, in one face thereof, which is adapted 45 to receive a solid portion 7 of the body 5, and when said solid portion 7 of the body 5 is received within said semi-circular recess 6, the rotation of the body 4 is precluded.

The body 5 is also provided at its point 50 of intersection with the body 4 with the semi-circular recess or depression 8 of a radius equal to that of the body 4 and when said body 5 is rotated to aline the depression or recess 8 in register with the body 4, as 55 in Fig. 3 of the drawing, the rotation of

the body 4 is permitted. Coöperating with the body 5 is a lock controlling mechanism 9, of any well known type, preferably controlled by a key, so that the body 5 is capable of being locked from rotation. 60

To prevent longitudinal movement of the bodies 4 and 5, when the same are in interlocked engagement and the rotation of the body 4 is prevented, I provide a flange or surface 10 circumferentially of the body 5, 65 adjacent the edges of the depression 8, and when said body 5 is rotated to a position, as in Figs. 1 and 2 of the drawings, said flange overhangs the surface of the body 4.

The rotation of the body 4 is accomplished by means of a handle or finger piece 11 secured to one end thereof exteriorly of the member 1.

It will be apparent that the rotation of the body 5 is controlled by a lock mechanism, conventionally illustrated as at 9, and that when said member is in a position, as in Figs. 3 and 4, with the depression 8 receiving the solid portion of the body 4, said body 4 is longitudinally movable from 80 its bore 2 and after being removed said body 5 is also capable of longitudinal movement from its bore 3. However, on the rotation of the body 5 through the lock mechanism 9, to a position as in Figs. 1 and 2, at which time the body 4 is locked from rotation and the body 5 is also locked from rotation by means of the mechanism 9, the solid portion of the body 5 received within the depression 6 in the body 4 prevents 90 longitudinal movement of said body 4 and the annular flange 10 on the body 5 prevents longitudinal movement of said body 5 relative to the body 4.

Having thus described my invention, what I claim as new and desire to protect by Letters Patent is:—

1. In a locking apparatus, the combination of a pair of axially rotatable bodies arranged at an angle to and intersecting each other, said bodies capable of rotation to have interlocked engagement with each other and when in said position one of said bodies precluding the rotation of the other, the interlocking of said bodies preventing longitudinal movement of either body. 100

2. In a locking apparatus, the combination of a pair of axially rotatable intersecting bodies arranged at an angle to each other and each provided at its point of 110

intersection with the other with a depression of a radius equal to that of the other intersecting body, said bodies adapted for rotation to position the solid portion of one within the depression within the other and thereby locking said latter body from rotation and from longitudinal movement relatively to the other, the locking body provided with a flange for projecting over the edge of the depression in the locked body, thereby preventing longitudinal movement of said locking body in one direction.

3. In a locking apparatus, the combination with a pair of intersecting bodies arranged at an angle to each other and adapted to rotate axially, to have interlocked engagement with each other, and when in said position one of said bodies preventing the rotation of the other and interlocking therewith to prevent longitudinal movement of either.

4. In a locking apparatus, the combination with a pair of intersecting bodies arranged at an angle to each other and adapted to rotate axially, to have interlocked engagement with each other, and when in said position one of said bodies preventing the rotation of the other and interlocking

therewith to prevent longitudinal movement of either, and a lock controlled mechanism 30 controlling the rotation of said locking body.

5. In a locking apparatus, the combination of a pair of axially rotatable intersecting bodies arranged at an angle to each other and each provided at its point of intersection with the other with a depression of a radius equal to that of the other intersecting body, said bodies adapted for rotation to position the solid portion of one within the depression within the other and thereby locking said latter body from rotation and from longitudinal movement relatively to the other, the locking body provided with a flange for projecting over the opposite edge of the depression in the locked body and thereby preventing longitudinal movement of said locking body in either direction.

In testimony whereof I have signed my name to this specification in the presence of 50 two subscribing witnesses.

WILLIAM F. DREW.
